(No Model.)

W. H. PORTER.

COMBINED DESK AND TYPE WRITER CABINET.

No. 365,275.

Patented June 21, 1887.

UNITED STATES PATENT OFFICE.

WILLIAM H. PORTER, OF WASHINGTON, DISTRICT OF COLUMBIA.

COMBINED DESK AND TYPE-WRITER CABINET.

SPECIFICATION forming part of Letters Patent No. 365,275, dated June 21, 1887.

Application filed March 10, 1887. Serial No. 230,418. (No model.)

To all whom it may concern:

Be it known that I, WILLIAM H. PORTER, a citizen of the United States, residing at Washington, in the District of Columbia, have 5 invented certain new and useful Improvements in Combined Desk and Type-Writer Cabinets; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification, and in which—

15 Figure 1 is a perspective view of my improved desk and type-writer cabinet open. Fig. 2 is a vertical sectional view of the same closed. Fig. 3 is a similar view showing modifications, and Fig. 4 is a detail view of parts of 20 the desk.

Since the perfection and adoption of type-writing machines, they have become an almost necessary feature in every well-regulated office; but, like all machinery, they must be kept 25 as free from dust as possible to give the best results. To do this requires that they must be covered, and to provide such a cover as shall be convenient, neat, and tidy has long been the desire of business men and the subject of the 30 inventive mind. As a stand and a receptacle for stationery, &c., must be provided, as well as a cover, I have combined them all in a cabinet, which can also be utilized as an ordinary desk, and at the same time in such a 35 manner that the change from the one to the other is quickly and easily made.

This invention therefore relates to that class of desks in which when the top is closed the machine is lowered, and when it is opened the 40 machine is raised into position; and it consists in the improved construction and combination of parts of such a desk, as will be hereinafter more particularly described, and pointed out in the claims.

45 In the accompanying drawings, in which the same letters of reference indicate corresponding parts in all the figures, A represents the desk or cabinet, which can be of any desired size and degree of ornamentation, and which 50 can be provided with drawers at one or both ends. In a desk having drawers at each end

a space, B, is left between them, within which a platform, C, is secured, preferably by means of pivots intermediate its ends. This pivot consists of a short bolt, D, at each side of the 55 platform, screw-threaded at each end, one end being screwed into the platform and the other end passed through a suitable hole in each of the inner panels, and provided with a nut upon its outer end. 60

To keep the edges of the platform from rubbing against the inner panels as it is being swung up and down when opening and closing the desk, a washer, E, is placed between them at each pivot. These washers are preferably made of some material which is a non-conductor of sound, as rubber or leather, and thus help to deaden the sound of the machine when being operated. Similar washers can also be used upon the outer ends of the bolts 70 between the nuts and the panels, and a thimble or sleeve, F, of the same kind of material can be placed around each pivot in the hole through the panel, thus almost completely insulating the platform acoustically from the 75 rest of the desk.

Instead of the two bolts for pivots, a solid bar can be passed entirely across the space and have its ends secured in the panels in the same manner as the bolts D. This construction adds great strength to the front of the desk, as the nuts at the ends of the pivots enable the panels to be drawn tightly against the sides or edges of the platform, and which will prevent the two ends of the desk from 85 being drawn away from each other in moving the desk, which would have a tendency to break them apart if they were not properly braced or secured together. By screwing the ends of the short bolts into the platform, the 90 platform itself takes the place of the continuous bar from panel to panel. By securing the panels or ends of the desk to the edges of the platform in this manner the ordinary cross-piece is dispensed with, which thus enables 95 the operator to secure a closer position to the desk when closed than if the cross-piece were used, as it would necessarily be so low as to be in the way.

The cover or top of the desk is composed of 100 three sections, the middle one of which, G, is secured to the edge of one of the other sec-

tions by means of blind or the ordinary hinges, so as to occupy the space between the two other sections, which are secured over the drawers at each end when closed, or to lie 5 upon the top of the section to which it is hinged when open. By finishing this middle section upon both sides it will make a neat appearance when closed or open, and can also be used for any of the ordinary purposes of a 10 desk in either position. The ordinary drawers or slides can be placed at each side underneath the end sections of the top or cover, which can be used either when using the device as a cabinet or as a desk. Secured at 15 one end to the underside of this middle swinging section, G, by means of a hinge-joint, is the rod H, to the other end of which is hinged the rod I, which in turn is pivotally secured to the rear portion of the platform C. The 20 bar H is secured to the section of the cover G at such a distance from its hinge edge that when the cabinet is open the inner end of the bar will project a slight distance beyond that edge. This will cause the rod I to occupy 25 more nearly a vertical position at all times, and will also cause the portion of the bar H that projects beyond the edge to act as a lever in raising the platform when the desk is being opened, using the hinge between the covers 30 as a fulcrum. When the section G is lying flat upon the end section when the desk is open, its weight is sufficient, owing to the great advantage it has in leverage, to hold up the weight of the machine on the platform without any catches, hooks, or other means of support. 35

As the machine cannot be operated as conveniently when placed as high as an ordinary desk, the platform is placed at some distance 40 from the top of the panels, so that when open the machine will be of the right height for convenience; but when the desk is closed it will be the same as an ordinary desk, both in appearance and in convenience, the cover being 45 at the usual height. As this placing of the platform below the level of the top of the desk would leave a space between the front of it and the cover or top when closed, which would admit dust, &c., and also make the desk 50 have an unfinished appearance, I place the pivots on which the platform swings at such a distance from the front as that when the rear end of the platform has been let down to its lowest point the front end has been raised until it just touches the lower side of the cover, 55 thus making a close joint and enabling the operator to lock the desk by means of the ordinary lock and key. Another advantage secured by this construction is that when the 60 platform is swung into its horizontal position ready for use its front edge is caused to project some distance in front of the desk, which will enable the operator to draw the machine partly out from between the ends of the desk. 65 The platform can be made long enough so that when in its horizontal position its rear end will extend to the back of the desk, or it can

be made a trifle shorter, and a piece, J, secured to it at an angle, so that when in its lowered position the piece J will occupy a horizontal 70 position; and as the platform swings in a circle when in its lowered position its rear end will be at some distance from the back, leaving a space through which dust could have access. A bottom piece, K, can be secured to 75 the back and inner panels, as shown in Fig. 3, against which the rear end of the platform will rest when the desk is closed.

To give the desk more the appearance of an ordinary desk when closed, a pendent leaf, L, 80 (shown in dotted line in Fig. 2,) can be hinged to the under side of the platform near its front edge, which will hang down and give the appearance of the ordinary drawer, the lower edge of which must be allowed to swing freely, 85 so as not to interfere with the person of the operator when using the machine or desk.

To prevent the machine from slipping down the platform when the desk is closed, it is secured by means of the ordinary stops or blocks, 90 and to prevent damage to the machine by raising the platform quickly stop-blocks M can be secured to the inner panels at the proper height, against which the platform will strike when it is raised. A button, of felt or 95 leather, can be placed upon the swinging top section, G, in such a position that when the desk is opened the bar H will strike upon the button instead of the cover, and thus the sound will be deadened. Instead of hinge-joints being used to secure the end of this bar to the cover or of the bar and rod together, the ordinary hook-and-eye joint can be used, the only 100 requisite being that sufficient play be given to the parts to prevent binding or breaking 105 as the desk is being closed or opened.

If it is not desired to secure the platform upon pivots, as above described, it can be hinged at its front end to a cross piece, N, 110 secured at its ends to the front portion of the inner panels, and be swung up and down at its rear end in the same manner as though it were pivoted at its sides. When this construction is used, a front door-piece, O, must also be hinged to this cross-piece, opening 115 outward, so that when the desk is open the door can be let down into a horizontal position, so that access can be had to the machine, and, if desired, the machine can be drawn out 120 in the same manner as with the other platform.

It will be seen that the swinging top and platform can be used upon a desk having drawers only at one side as well as at both, 125 it only being necessary to hinge the section G to the top of the panel at the side not having the drawers, instead of to the cover at that end when there are drawers at both ends. In this style the hinged section will answer all the purposes of what is called a "drop leaf" without adding to the cost of the desk, except that incidental to the making the top in sections and hinging one section at its edge, and will possess all the advantages of covering the ma- 130

chine as well as with the drawers upon both sides of the desk. It will be necessary, however, to provide the desk at that end with the ordinary swinging brace or support to keep 5 the cover in a horizontal position when it is opened for use. As in this style the edge of the cover is hinged to the side panel of the desk in the same manner as it is shown hinged to one section of the cover, and the brace is 10 of any ordinary construction, they have not been illustrated.

It is evident that in a desk having one section of the cover hinged to swing over laterally, it can be opened and closed easily and 15 quickly by the operator without rising from his seat or by an operator who has not such an abundance of muscular power as to be able to operate it if he had to reach out at arm's length and force it up and down; but with 20 my improvement the power is applied at the most advantageous point and in the most advantageous way, as the cover must swing through a half-circle in raising the platform and machine a few inches, and when the desk 25 is closed it can be used for all the ordinary uses of a flat top desk, and by making the top inclined have all the advantages of the inclined-top desk.

Having thus described my invention, I claim 30 and desire to secure by Letters Patent of the United States—

1. In a combined desk and type-writer cabinet, the combination, with a desk having its top in sections, one of which is hinged thereto, 35 of a platform pivotally secured intermediate its ends below said swinging section, the front end of which is adapted to be raised to touch said swinging section when the desk is closed, and means, substantially as described, for connecting said platform and said section.

2. In a combined desk and type-writer cabinet, the combination, with a desk having its top in sections, one of which is hinged thereto, of a platform pivotally secured below said swinging section, the front end of which is adapted 45 to project in front of the desk when open or in a horizontal position, and means, substantially as described, for connecting said platform and said swinging section.

3. In a combined desk and type-writer cabinet, the combination of a desk the ends of which are entirely disconnected at their front portions and each provided with a hole, a sleeve of non - sound - conducting material within each of said holes, a platform between 50 said ends, a pivot upon each edge or side of said platform and projecting through said sleeves in said holes, firmly securing the ends of the desk to the platform, washers of non-sound-conducting material upon said pivots and between the 55 edges of the platform and the ends of the desk, a cover hinged above said platform, and means, substantially as described, for connecting said cover and platform.

4. In a combined desk and type-writer cabinet, the combination, with a desk having its top in sections, one of which is hinged to swing laterally, of a platform pivotally secured below said section and a jointed bar pivotally secured at its ends to said platform and said 60 swinging section.

5. In a combined desk and type-writer cabinet, the combination, with a desk having its top in sections, one of which is hinged to swing laterally, of a platform pivotally secured below said swinging section, a bar pivotally connected at one end to said swinging section, the opposite end of which projects beyond the hinged edge of said section when the desk is open, and a rod pivotally connected 75 with the end of said bar and with the rear portion of said platform.

6. In a combined desk and type-writer cabinet, the combination of a desk, the ends of which are entirely disconnected at their front 80 portions and having a space between them, a platform within said space firmly secured at its sides to the said ends, a cover above said platform, and means, substantially as described, for connecting said cover and platform.

In testimony whereof I affix my signature in presence of two witnesses.

WILLIAM H. PORTER.
